COMBINED NUTCRACKER AND BOWL

Joel T. Hartmeister, P.O. Box 268,
Aspen, Colo. 81611

Filed June 14, 1971, Ser. No. 153,162

Term of patent 14 years

Int. Cl. D7—04
U.S. Cl. D44—1 E

FIG. 1.

FIG. 2.

FIG. 3.

FIG. 4.

FIG. 5.

FIG. 1 is a top plan view of a combined nutcracker and bowl showing my new design;

FIG. 2 is a front view thereof;

FIG. 3 is a rear view thereof;

FIG. 4 is an end view as seen from the right of FIG. 2; and

FIG. 5 is an end view as seen from the left of FIG. 2.

The bottom thereof is planar and unadorned.

I claim:

The ornamental design for a combined nutcracker and bowl, as shown and described.
